(57) **CLAIM**

The ornamental design for an article display device, as shown and described.

DESCRIPTION

FIG. 1 is a perspective view of an article display device of the present invention, shown hung on a display structure; FIG. 2 is a top plan view of the article display device of FIG. 1, the bottom plan view being identical thereto; FIG. 3 is a front elevational view of the article display device of FIG. 1, the rear elevational view being identical thereto; FIG. 4 is a left side view of the article display device of FIG. 1, the right side view being identical thereto; and, FIG. 5 is a front elevational view of a second embodiment of the article display device of FIG. 1, the rear elevational view being identical to FIG. 5, the top and bottom plan views being identical to FIG. 2 and the left and right side views being identical to FIG. 4.

The matter shown in phantom lines in FIG. 1 is for illustrative purposes only and forms no part of the claimed design.
